UNITED STATES PATENT OFFICE.

ABRAHAM A. SCHIMMEL, OF BOSTON, AND MAX FREEDMAN, OF MALDEN,
MASSACHUSETTS.

HAMMOCK-SUPPORT.

991,803.

Specification of Letters Patent.

Patented May 9, 1911.

Application filed July 13, 1910. Serial No. 571,733.

To all whom it may concern:

Be it known that we, ABRAHAM A. SCHIMMEL and MAX FREEDMAN, of Boston, in the county of Suffolk and State of Massachusetts, and of Malden, in the county of Middlesex and State of Massachusetts, respectively, have invented certain new and useful Improvements in Hammock-Supports, of which the following is a specification.

10 The object of this invention is to provide a portable frame adapted to be placed anywhere, and from which a hammock may be slung.

The object is to provide a supporting frame of simple construction, which may easily be taken apart when not required for use, or when being moved from place to place, and which also may be packed together compactly for stowage in a small 20 space, and for shipment.

A supporting frame, in which the principles of our invention are embodied in the form at present preferred by us, is illustrated in the accompanying drawings.

25 Figure 1 is a side elevation of the support. Fig. 2 is an end elevation of the same. Fig. 3 is a detail vertical section on the line 3—3 of Fig. 2. Fig. 4 is a detail horizontal section on the line 4—4 of Fig. 2. Fig. 5 is a 30 perspective view of the foot portion of each upright of the support. Fig. 6 is a cross-section on line 6—6 of Fig. 3. Fig. 7 is a perspective view of one of the members in detail. Fig. 8 is a plan view of another 35 member of the device in detail.

The same reference characters indicate the same parts in all the figures.

Referring to the drawings, *a* and *b* represent two uprights constituting the end members of the frame, and the supports for the hammock. On the upper ends of these supports are hooks *c* and *d*, or equivalent devices, from which the hammock slings may hang. In the form here shown, the hammock-holders *c* and *d* are metal hooks having shanks passing through the uprights *a* and *b* and secured by nuts *e* and *f*, which are preferably wing nuts adapted to be turned by being grasped between the thumb and forefinger. The uprights are preferably sections of piping and are supported at their bottoms and prevented from either toppling over sidewise or sinking into soft ground, by a foot piece attached to each upright. 50 The foot piece is preferably a cross-bar *g*

secured to the lower end of the upright by a fastening *h* such as a bolt or pin, and braced by struts *i* and *j*. These struts are pivoted to the ends of the foot piece *g* and detachably engaged with the upright by a removable bolt or pin *k*. The foot piece and brace may be in any form, or of any material, and we prefer to make them from sections of angle iron, as being the most efficient and inexpensive material and, firm. 60 When the frame is not required for use and is to be stowed away or shipped, the fastening *k* can be removed, the braces *i* and *j* swung down beside the cross piece *g* and the latter then turned through a quarter turn 70 into line with the upright, wherein it occupies the least possible space.

For connecting the two uprights *a* and *b* together, supposing them at the proper distance apart, and preventing them from toppling over longitudinally, we provide a cross-bar *l*, which is preferably a section of metallic piping and is passed from one upright to the other at a low point thereon, which is below the position occupied by the 80 hammock. The cross-bar is detachably engaged with the uprights, so that it can be removed therefrom and the parts packed together into the least possible space for shipment or stowage. 85

The means for connecting the ends of the cross-bar to the uprights, whereby these members can be easily assembled and disconnected, and also held rigidly upright, is an important feature of our invention, 90 and consists of socket members *m*, mounted upon the uprights and bracing tongue members *n* carried by the ends of the cross-bar. Each socket member consists of a sleeve portion embracing the upright and resting upon 95 the braces *i* and *j* at their point of connection with the upright, and has also a foot portion *m'*, on which the end of the cross-bar *l* rests, and also side members *m*² flanking the ends of the cross-bar. The tongue 100 and brace member *n* is preferably made from a flat strip of metallic stock, which is doubled at its center to form a fold or loop *n'*, which is inserted into the open end of the cross-bar and is fastened therein by a 105 pin *o* or other fastening. Beyond the end of the cross-bar the ends of the tongue and brace member are bent oppositely into line with each other, one of them forming the tongue *n*² and the other a brace *n*³. The 110

tongue is adapted to pass through an opening in the foot portion m' of the supporting stirrup m and both members n^2 and n^3 are adapted to lie close against the side of the upright or standard b . They have sufficient stiffness to resist any tendency of the uprights to fall over longitudinally of the frame.

The hammock, as hereinbefore described, 10 is of the simplest possible construction, consisting only of three main members which may be readily taken apart and reassembled by one person, and which, at the same time, have sufficient stiffness to hold the upright 15 members or posts a and b of the frame upright. Thus a second longitudinal bracing member, which is a feature of certain other forms of hammock support, is, by our invention, rendered unnecessary. Furthermore, 20 more the capability of folding of the foot piece and braces into line with the upright permits all the members of the frame to be packed together into a space no greater than the volume of three rods of the size of the 25 uprights a and b .

We claim,—

1. A hammock support comprising two uprights, hooks detachably secured to the upper parts of said uprights for supporting 30 a hammock, a cross-bar between said uprights below the position of the hammock, supports on the uprights for the ends of said cross-bar, and bracing members secured to the ends of said cross-bar and having 35 their ends in alinement with each other, one of said ends being passed through an opening in said support and both ends lying beside and in contact with the upright.

2. A hammock support comprising two

uprights each having provisions for supporting one end of a hammock, a single cross-bar extending between said uprights, sockets on the uprights adjacent to the ends of said cross-bar, and tongue and brace members secured to the ends of the cross-bar 45 removably contained in said sockets and lying alongside the uprights, whereby the uprights are retained at a fixed distance apart and in a perpendicular relation by the 50 single cross-bar.

3. A hammock support comprising two uprights each having provisions for supporting one end of a hammock, a single cross-bar extending between said uprights and having recesses in its ends, sockets on the uprights adjacent to the ends of said cross-bar, and a tongue and brace member secured to each end of the cross-bar, 55 consisting of a strip of rigid material doubled at its middle and secured in the end recess of the bar, its two ends outside of the bar being bent oppositely so that such ends are in alinement, one of such ends being removably contained in one of the sockets to secure the uprights and cross-bar together, and the two 60 ends lying alongside the upright to retain it in a fixed angular relation to the cross-bar. 65

In testimony whereof we have affixed our signatures, in presence of two witnesses.
